Patented Dec. 17, 1918.

UNITED STATES PATENT OFFICE.

ROBERT J. HEWETT, OF WESTFIELD, NEW JERSEY.

SIGNALING DEVICE.

1,287,993.

Specification of Letters Patent. Patented Dec. 17, 1918.

Application filed September 1, 1916. Serial No. 117,989.

To all whom it may concern:

Be it known that I, ROBERT J. HEWETT, a citizen of the United States, residing at Westfield, in the county of Union and State 5 of New Jersey, have invented certain new and useful Improvements in Signaling Devices, of which the following is a full, clear, and exact description.

This invention relates to a three-position 10 signaling device, which is adapted to be used as a cab signal, or in other places where three-position signal indicators are desired.

The primary object of the invention is to provide a three-position signal which will 15 be positive in its operation and yet be controlled by a single control circuit, which adapts the device for use with cab signal systems where the three-position signal is carried in the cab and the circuit wires are 20 energized by suitable devices along the trackway, as well as in other railway signal systems where a minimum number of wires is desirable.

The invention therefore consists of a signal arm which is biased to one position and is moved to its two other positions by means 25 of separate electromagnetic devices. One of these electromagnetic devices is placed in the main circuit of the signal and the other 30 in a branch to the main signal circuit, and has its circuit controlled by a circuit controller, which is actuated preferably by a reversal of current in the main circuit, whereby with current of one polarity passing 35 through the main circuit, one of the electromagnetic devices will be operated, and upon a reversal of current the circuit controller will be actuated to control the circuit to the other electromagnetic devices. 40 In this manner the signal is positively moved to its two operative positions. The signal is applicable for controlling train movements by cab signals, without the aid of the usual roadside signals having movable 45 semaphore arms, by which application of the three-position signal the marker masts or inoperative signal arms for identifying the signaling locations and for qualifying the indication given by the signal, should be 50 placed along the trackway. Its use, however, is not limited to this particular one, but may be used in conjunction with the ordinary roadside signal systems.

In the accompanying drawings, the invention 55 is disclosed as a part of a cab signaling system, but it is not the intention

that this description will limit the invention to this particular use, as the signal *per se*, with its control circuits, may be used for other purposes, the scope of the invention 60 being set out in the appended claims.

Figure 1 shows a signal and the associated control system, the signal being shown in safety position;

Fig. 2 is a detail, the signal being shown 65 in its caution position;

Fig. 3 is a detail showing the signal in its normal or danger position; and

Fig. 4 is a detail showing a type of casing 70 in which the signal may be mounted.

The roadside control system may be of any suitable character, and in the embodiment shown, the line circuits are of the polarized type, whereby the two positions of the signal may be obtained by a reversal of 75 current in the control circuits.

Referring to Fig. 1, the line control relays designated L¹⁵, L¹⁶, L¹⁷ and L¹⁸, are of the type known as neutral polar relays, in which there are two circuit controllers, one 80 a neutral circuit controller which comprises a neutral armature which is attracted by current of either polarity, and the other a polar circuit controller which is actuated by the reversal of current through the electro- 85 magnetic device operating the same.

The distant line relay L¹⁵ corresponds to a distant marker mast 15, which is positioned in the same place as would be the ordinary distant roadside signal. This relay controls the polarity of the current from the battery 131 to the distant contact rail 125. In the same manner the distant line relay L¹⁷, which corresponds to the distant marker 17, controls the polarity of the cur- 95 rent from a battery 146 to a distant contact rail 140.

The line relay L¹⁶ is a home line relay and corresponds to a home marker 16. This relay controls the polarity of current from a 100 battery 39 to a home contact rail 33, and also, by extension line circuit wires 64 and 69, controls the polarity of the current from a battery 39 to a distant line relay L¹⁵. In the same manner, the home line relay L¹⁸, 105 which corresponds to the home marker 18, controls the polarity of the current from the battery 81 to the home contact rail 75, and also, by extension line circuit wires 94 and 99, controls the polarity of the current 110 from the battery 81 to the distant line relay L¹⁷.

The home line relay L^{16} is the control relay for the block between the markers 16 and 18, which includes the track sections 11 and 12. The circuit whereby it performs this control is as follows: from the home line relay L^{16} , wire 46, contact 47 of track relay R^{11} , line wire 48, contact 49 of track relay R^{12} , wire 50, contact 51 of line relay L^{18} for the next block, wire 52, battery 53, wire 54, front contact 55 of line relay L^{18} , and common wire 250 back to the line relay L^{16} . The line relay L^{16} is, therefore, energized from the battery 53, which is controlled by the home line relay L^{18} , which acts as a pole changer for reversing the current passing from this battery to relay L^{16} . That is, when the line relay L^{18} is energized, the closed condition of its front contacts 51 and 55 will deliver a current of normal direction to the line circuit-wire 48 and thereby to the line relay L^{16} , which normal current will cause the line relay L^{16} to be energized. When the line relay L^{16} is energized by current in this direction, the polar contacts 37 and 41 will be thrown to the right, as shown in the drawing. The energized condition of the relay will also cause the neutral contacts 24, 28, 35 and 43 to be closed. On the other hand, when the line relay L^{18} is deenergized the circuit through the front contacts 51 and 55 will be broken and the circuit closed through the back contacts 62 and 63. This will reverse the current passing from the battery 53 to the line circuit wire 48, causing a reversal of polarity of the home line relay L^{16} , but maintaining it in its energized condition. The polarized circuit controllers 37 and 41 will then be thrown to the left, the neutral contacts 24, 28, 35 and 43 remaining closed irrespective of the direction of current passing through the relay.

The control circuit for home line relay L^{18} is similar to home line relay L^{16} and is only partly shown, as wire 88, contact 89 and wire 90.

The circuit controllers or polar contacts 37 and 41 of the home line relay L^{16} serve as a pole changer for delivering a current in a normal or reverse direction from the battery 39 to the home contact rail 33, and also to distant line relay L^{15} , the contacts, when thrown to the right, delivering a current in the normal direction and when thrown to the left, a current in the reverse direction.

The home line relay L^{16} serves as a pole changer for the battery 26 and controls the home line relay in the rear, not shown. When the line relay L^{16} is energized, the closed condition of its front contacts 24 and 28 will deliver a current of normal direction to the home line circuit wire 21 and to the home line relay at the rear, not shown. However, when the line relay L^{16} is deenergized, its front contacts 24 and 28 are in open position and the back contacts 30 and

31 are closed, which will deliver current in a reverse direction to the home line relay at the rear.

The polar contacts 133 and 129 of the distant line relay L^{15} act as a pole changer for the circuit connecting the battery 131 to the distant contact rail 125, the contacts 133 and 129 delivering a current passing to the contact rail 125 in the normal direction when thrown to the right, and in a reverse direction when thrown to the left. In the same manner, the polar contacts 148 and 144 of the distant line relay L^{17} serve as a pole changer for delivering current in a normal or reverse direction from the battery 146 to the distant contact rail 140, the current being, in the normal direction when the contacts are thrown to the right and in the reverse direction when thrown to the left. The extension control circuit for the distant line relay L^{17} is in multiple with the home contact rail 75; and in the same manner the extension control circuit for the distant line relay L^{15} is in multiple with home contact rail 33. The distant control relay L^{15} and its distant contact rail 125 have the same control as home contact rail 33. In the same way distant control relay L^{17} and its distant contact rail 140 have the same control as home contact rail 75. In other words, a distant contact rail gives the same signal indications as the home contact rail.

It will therefore be seen that the purpose of the control system described is to deliver current of normal or reverse polarity to the contact rails 125, 33, 140 and 75, from which said current is delivered to the three-position signal upon the cab, which will now be described.

The semaphore arm of the three-position signal on the cab signal is designated C, and in Fig. 1 is shown in its 90° position, corresponding to the safety position. The arm is moved to this position by the electromagnetic device 120 when the same is energized, the armature E thereof carrying at its outer end an arm f, through which an operating rod B passes, the rod having a collar h thereon which is engaged by the arm f to move and hold the semaphore arm in its 90° position as long as the electromagnet 120 remains energized.

The semaphore arm C is moved to its 45° or "caution" position by a second electromagnet 112 having an armature A which carries an arm g through which the operating rod B also passes. When the semaphore arm is in its 90° position, as shown in Fig. 1, and the electromagnet 112 is energized, the armature A is attracted and held against a stop i, but since the armature E is also attracted by the energized condition of the electromagnet 120, the armature A in moving against the stop i does no mechanical work, since the arm f has already been

moved to a position above the same, as shown in Fig. 1. When the electromagnet 112 is deenergized the armature A rests against a stop *j*.

5 In Fig. 2 of the drawing, the semaphore arm C is shown in its 45° position, that is, the "caution" position, and, as will be clear from this view, the electromagnet 120 is deenergized and the electromagnet 112 energized. The armature E, therefore, drops until its arm *f* rests upon the arm *g* carried by the armature A, which, since the electromagnet 112 is in energized position, is still held against the stop *i*. The operating rod 10 B will therefore be lowered a distance corresponding to the distance to which the arm *f* drops, which will permit the semaphore to assume the position shown in Fig. 2, that is, its 45° position.

15 In Fig. 3 the semaphore arm C is shown in its normal "danger" or horizontal position, and here both of the electromagnets 120 and 112 are deenergized, the armature A dropping from the position shown in Fig. 2 until it rests upon the stop *j*, and since the arm *f* rests on the arm *g* and the arm *f* engages the collar *h* upon the operating rod 20 B, the semaphore arm C may assume a horizontal position by gravity, but will be prevented from further movement.

25 The armature A controlled by the electromagnet 112 has, therefore, two positions, depending upon whether it is resting against the stop *i* or the stop *j*, while the armature E controlled by the magnet 120 has three positions; one, its attracted position where the arm *f* is held above the arm *g*; two, where the arm *f* rests upon the arm *g* while the armature A is attracted; and three, where the arm *f* rests upon the arm *g* when the armature A is released.

30 The magnet 112 is a neutral polar relay having a neutral armature A, which has already been described, and a neutral contact 35 116 and also a polar armature 118, which is thrown to the left or right, depending upon the direction of current passing through the electromagnet 112. The magnet 120 has only the single armature E, which has already 40 been described.

35 If desirable, the electromagnets 112 and 120, together with their contacts, may be inclosed within a casing or case, which has been designated P, and shown in Fig. 4 of the drawing. This case may be provided with an opening Q in its front face, protected by a transparent pane such as glass, through which the semaphore arm C is visible. It is preferable to arrange the opening 45 Q so that only the 45° and 90° positions of the semaphore arm are visible. The reason for this is that where a signal is visible to the engineman it is advisable to have a normal danger position of the signal obscured, for 50 otherwise the engineer would be continu-

ously running against a signal set against him. By obscuring the "danger" or zero, or horizontal position of the semaphore arm, the engineman is therefore governed entirely by the 45° and 90° positions of the signal, 70 which he receives as he passes over contact rails, in a manner which will be fully apparent from a description of the mode of operation of the signal system, which will now be made.

75 Assuming that there is an eastbound train in track section 9 and the contact shoe 110 of the engine is in engagement with the distant contact rail 125, and that the trackway in advance is clear so that the train may 80 proceed with safety, this "safety" signal is received by the three-position indicator described, in the following manner. The distant contact rail 125 is energized from a circuit passing from the battery 131, wire 130, 85 polar contact 129, wire 128, contact 127, wire 126, distant contact rail 125, contact shoe 110, cab wire 111, electromagnet 112, cab wire 113, to the axle and wheel 114 of the train, track rail 137, wire 136, contact 135, 90 wire 134, polar contact 133 and wire 132 to the other side of the battery 131. This circuit being closed, the current passes therethrough in the normal direction and energizes the magnet 112, which will attract its 95 armature A and through the operating rod B, as described, will move the semaphore arm C to its 45° position. However, since current is passing in the normal direction through the electromagnet 112, the neutral 100 contact 116 will be closed and also the polar contact 118 will be thrown to the right or to its closed position, which will connect the magnet 120 to the cab circuit, the circuit being as follows: from cab wire 111, wire 105 121, magnet 120, wire 119, polar contact 118, wire 117, neutral contact 116 and wire 115 to cab wire 113. The energization of the magnet 120 will attract its armature E and the semaphore arm C will be moved to its 90° 110 position, through the operating rod B.

115 The semaphore arm C when in its 90° position, informs the engineer or engineman that the track section 10, and also the block from the home marker 16 to the home marker 18 is clear, and that he may proceed to the home marker 16, at which point he will receive a second safety indication.

120 The energization of the contact rail 125 to give the 90° or safety signal indication, as described, is due to the fact that the distant line relay L¹⁵ which controls the circuit from the battery 131, previously traced, is controlled by the track relay R¹⁰, which, 125 since track section 10 is unoccupied, is energized to close the contacts 65 and 68. The circuit including the contacts 65 and 68 is also controlled by contacts 35 and 43 of line relay L¹⁶ which is in turn controlled by the track relays R¹¹ and R¹², and since the track 130

sections 11 and 12 are unoccupied, these relays are energized and close the circuit to the line relay L^{16} .

As the engine of the eastbound train enters the track section 10, and its contact shoe 110 leaves the distant contact rail 125, both of the magnets 112 and 120 are deenergized and the semaphore arm C will return to its normal or danger position, as shown in Fig. 3, under the force of gravity. As the train approaches the home marker 16, the contact shoe 110 engages with the home contact rail 33. This contact rail is also energized by a current of normal polarity from the battery 39, and a circuit will be closed to the magnet 112, as follows: from the battery 39, wire 38, polar contact 37 of relay L^{16} , wire 36, contact 35 of relay L^{16} , wire 34, home contact rail 33, contact shoe 110, wire 111, magnet 112, wire 113, axle and wheel 114, track rail 45, wire 44, contact 43, wire 42, polar contact 41 and wire 40 to the other side of the battery 39. This current being of normal polarity will energize the magnet 112 and, as previously described, will also close the circuit to the magnet 120 so that the semaphore arm C is successively raised to its 45° position and then to its 90° position.

The receipt of the safety signal by the engagement of the contact shoe with the home contact rail 33, informs the engineer that the block extending from home marker 16 to home marker 18, is clear and also that the next block from home marker 18 to home marker of the next succeeding block (which block is only partially shown) is also clear. The fact that a two-block clear indication is given at this point is due to the fact that the home relay L^{16} which controls the battery 39 is controlled by the home line relay L^{18} , the circuit for the relay L^{16} being controlled by the track relays R^{11} and R^{12} , while the circuit for the home line relay L^{18} is in turn controlled by the track relays for the block in advance.

Assuming that the block in advance of the home marker 18 is occupied, the track relays for that block which control the home line relay L^{18} will be open, deenergizing the line relay L^{18} , opening its front contacts 51 and 55 and closing its back contacts 63 and 62. The polarity of the current from the battery 53 will then be delivered in a reverse direction to the line wire 48, which will reverse the polarity of the home line relay L^{16} which will throw its polar contacts 41 and 37 to the left and this will deliver a current of reverse polarity from battery 39 to the home contact rail 33 and also to distant contact relay L^{15} , and this relay in turn will throw its polar contacts 133 and 129 to the left and deliver a current in a reverse direction from battery 131 to distant contact rail 125. An eastbound train in track section 9 with its contact shoe 110 on contact rail

125 will then receive a current which passes through the cab signal in the direction opposite to that previously described, the circuit being as follows: from the negative side of the battery 131, wire 132, polar contact 129, wire 128, contact 127, wire 126, contact rail 125, contact shoe 110, wire 111, to magnet 112, wire 113, axle and wheel 114, track rail 137, wire 136, contact 135, wire 134, polar contact 133 and wire 138, to the positive terminal of the battery 131. This current of reverse direction will energize the electromagnet 112 and the semaphore arm C will be moved to its 45° position. However, since the current passes through the electromagnet 112 in reverse direction it will have an opposite polarity and will throw its polar contact 118 to the left, which will open the circuit for the magnet 120 and prevent the semaphore arm C from being moved to its 90° position. In Fig. 2 of the drawing, this position of the circuits and of the magnets 112 and 120 is shown. A 45° indication is therefore received by the engineer, which informs him that he must proceed with "caution," expecting to receive a caution signal at the home marker 16. If there is no change in the condition of the blocks in advance, as the train advances it will receive a caution indication, when its contact shoe engages with the home contact rail 33, since this contact rail will be energized by a current of reverse direction in the following manner: The home line relay L^{16} , since it is energized by a current in the reverse direction, as previously described, has thrown its polar contacts 41 and 37 to the left, which will reverse the polarity of the current passing from the battery 39, and the circuit to the contact rail 33 will then be as follows: from the negative terminal of the battery 39, wire 40, polar contact 37, wire 36, contact 35, wire 34, contact rail 33, contact shoe 110, wire 111, magnet 112, wire 113, axle and wheel 114, track rail 45, wire 44, contact 43, wire 42, polar contact 41, wire 38 to the positive terminal of the battery 39. This reverse current will energize the magnet 112, as previously described, which will move the semaphore arm to its 45° position, and will also open the polar contact 118 to prevent the energization of the magnet 120. The "caution" signal received at this point will inform the engineer that the first block extending from marker 16 to marker 18 is clear, but that the block in advance is occupied, and that he must proceed with "caution" to the home marker 18. However, before reaching the home marker 18 he will receive an indication at the distant marker 17 which may inform him of a change in the condition of the blocks in advance.

Assuming that the block extending from the home marker 16 to the home marker 18,

is occupied by a train either in the track section 11 or the track section 12, in this instance either the relay R¹¹ or R¹² will be deenergized and the control circuit for the line 5 wire 48 which controls the home line relay L¹⁶ will be open. The line relay L¹⁶ will be deenergized, which will open all of its neutral contacts including contacts 35 and 43 which control the circuit to the home contact rail 33 and also the distant control relay L¹⁵. Therefore, when the contact shoe 110 of a train in track section 9 engages with distant contact rail 125, the semaphore arm C will not be moved to either its 45° or its 90° position, since neither of the electromagnets 112 or 120 is energized. This is shown in Fig. 3. The absence of a proceed signal informs the engineer of the fact that the block from home marker 16 to home marker 18 is occupied and that he should proceed at caution to home marker 16 and stop the train with his contact shoe 110 on home contact rail 33 so as to receive a proceed indication as soon as the proceeding train clears out of track 25 section 12.

I claim:

1. In a three-position signal for railway signaling systems, an indicating arm biased to one position and having two operative positions, separate electromagnetic devices for moving said signal arm to its two operative positions, and means including a circuit through said devices for energizing one of said devices when current passes through the 30 circuit in one direction and for energizing the other of said devices when it passes through the circuit in the opposite direction.
2. In a three-position signal for railway 35 signaling systems, an indicating arm biased to one position and having two operative positions, separate electromagnetic devices for moving said signal arm to its two operative positions, and means including a circuit

through said devices for energizing one of 45 said devices under determined current conditions and for energizing the other of said devices under different current conditions in said circuit.

3. In a three-position signal for railway 50 signaling systems, an indicating arm biased to one position and having two operative positions, separate electromagnetic devices for moving said signal arm to its two operative positions, a main circuit leading to one 55 of said devices, a branch circuit from said main circuit leading to the other of said devices, and a circuit controller on said last named circuit.

4. In a three-position signal for railway 60 signaling systems, an indicating arm biased to one position and having two operative positions, separate electromagnetic devices for moving said signal arm to its two operative positions, a main circuit leading to one 65 of said devices, a branch circuit from said main circuit leading to the other of said devices, and a circuit controller on said last named circuit controlled by the magnetic device in the main circuit. 70

5. In a three-position signal for railway signaling systems, an indicating arm biased to one position and having two operative positions, a main circuit, a relay in said circuit having a neutral and a polar armature, 75 means connected to said neutral armature for moving the arm to one of its operative positions, a branch of said main circuit having an electromagnetic device therein for moving said signal arm to its other operative 80 position, said last named circuit including the polar armature of said relay.

In witness whereof, I subscribe my signature, in the presence of two witnesses.

ROBERT J. HEWETT.
